United States Patent Office

Des. 217,985
Patented July 7, 1970

217,985/

STRINGED MUSICAL INSTRUMENT

Walter J. Pelensky, 19C Manheim Gardens,
Philadelphia, Pa. 19144

Filed May 13, 1969, Ser. No. 17,131

Term of patent 14 years

Int. Cl. D17—03

U.S. Cl. D56—1

Fig. 1

Fig. 3

Fig. 2

FIG. 1 is a perspective view of a stringed musical instrument specifically, an Ukrainian Kobza, showing my new design;

FIG. 2 is a face view; and

FIG. 3 is a left side elevational view thereof.

I claim:

The ornamental design for a stringed musical instrument, as shown.
